UNITED STATES PATENT OFFICE.

GEORGE WOOD, OF SEATTLE, WASHINGTON, ASSIGNOR TO TI-IT MACHINE CO., OF SAN FRANCISCO, CALIFORNIA, A CORPORATION OF CALIFORNIA.

BOX-STRAPPING TOOL.

Application filed January 22, 1920. Serial No. 353,810.

To all whom it may concern:

Be it known that I, GEORGE Wood, a citizen of the United States of America, and resident of the city of Seattle, county of King, and State of Washington, have invented certain new and useful Improvements in Box-Strapping Tools, of which the following is a specification.

My invention relates to tools designed for use in applying reinforcing wires as hoops or bands about boxes, packages and the like and consists of certain novel features of construction which have been illustrated in the drawings and which will be hereinafter described and then particularly defined by the claims terminating this specification.

The object of my invention is to provide a tool for doing this work, which will be rapid in operation and which will not only stretch the wire and form the twist or knot, but which will also trim the ends of the wire outside of the knot, so as to remove any projecting ends which might cause trouble.

An object of my invention is to produce a wire cutter, in combination with a wire tying machine, which will cut the wire at both ends closer to the knot than in the ordinary type of machines, thus leaving no projecting ends to damage other packages or persons in transit or handling.

Another object is to provide a wire cutter in connection with a wire tying machine which is operable independently of the tying mechanism, and which may be operated after the knot is entirely finished.

A still further object is the provision of a tightening mechanism which will not bend a wire in such a manner that the portion held therein cannot be used for the next band to be put about the box, in this manner preventing waste of wire, and making possible the use of wire from a coil, or in cut lengths.

The object of my invention is also to improve upon the general construction and operation of tools of this kind.

In the accompanying drawings I have shown my tool and the manner of its operation, the same being in the form of construction which I most prefer to use.

Figure 1 is a top or plan view of the tool with a portion of the frame broken away to show the position of certain parts.

Figure 2 is a front elevation of the machine, that is, a view taken from the side at 55 which the knot is formed.

Figure 3 is a transverse sectional elevation of the tool taken upon a plane corresponding with one side face of the twister gears.

Figure 4 is a sectional elevation taken substantially upon the plane indicated by the line 4—4 of Figure 2.

Figure 5 is a side elevation showing that cutter and the means for operating the same which is located at the right hand side of 65 the machine as shown in Figure 2.

Figure 6 is a section taken through the wire tightening mechanism just above the holding ratchet.

This tool is designed for forming the 70 type of knot which is made by placing the two ends of the wire close alongside each other and then twisting the central portion of the two wire sections, while holding said wire sections against twisting at a distance 75 a little removed from the point where the twist is applied. In consequence, the two wire ends are twisted together to form two twist sections, one being twisted righthandedly and the other left-handedly. This knot 80 is, in itself, an old form of knot and the use of the mechanism for forming the same in the manner described is, broadly stated, old. Such mechanism employs two holding members 2 and 20, and a twisting member 3, 85 which latter is in the form of a small gear, having a slot 30 therein for the reception of the two wires.

The small pinion 3, is herein shown as immediately turned by means of an idler 90 pinion 31, which in turn is turned by the gear, or gear segment, 32. The gear 32 is operated through the means of a lever 33, which is secured thereto, or to the shaft 95 upon which the gear is mounted. This mechanism is old excepting as to the particular form of the lever 33. As herein shown, this lever is provided with a head in the form of a yoke having two parts, 34, one of which lies at each side of the gear 32. 100

Each of these yoke heads 34, is provided with a lug 35, which has two faces, 36 and 37, one of which is designed to contact with the end of the stop bolt 38, and the other 5 with a similar bolt 39, thereby making it possible to exactly determine the point where the lever starts and stops. The necessity for this is due to the fact that the twisting pinion 3 should, at each limit of 10 its turning, occupy a position in which the slot 30 therein, faces outwardly in accurate position to conform to the location of the slot 12 in the frame 1.

This frame is provided with a toe 10, 15 which forms the lower half of the slot 12. This slot is of such size as to receive the wires 15 which form the hoop and also to permit the wires to be twisted while occupying the slot. At each end of the slot the 20 holding bars 2 are placed. The slots in these holding bars are just wide enough to permit the free insertion and removal of the wires being employed, but not wide enough to permit the wires being twisted.

25 Close outside of one end of the slot 12, is provided a wire holding dog 4. This dog is pivoted, as at 40, so that the toothed end face, as 41, which engages with the wire, is eccentric to the pivot. An anvil 42 which 30 co-operates with the dog 4, is located just beneath the position occupied by the wire. Normally the dog 4 is held down into wire-engaging and holding position, both by its own weight and by the action of a spring 43.

35 In commencing the operation of forming the loop the end of the wire is first secured by the dog 4 and then placed within the slot 12 in the frame and the slots of the holding bars 2 and 20. It also enters the slot 30, in 40 the twisting pinion, said pinion being, at that time, in position so that its slot is facing outward. The wire is then carried about the package and brought back and inserted in the same slots alongside the first portion of 45 the wire. It is carried beyond the twisting mechanism and is engaged by the tightening mechanism, shown as a whole at 5, this being located as close to the twisting mechanism as it may be conveniently placed and operated.

50 This tightening mechanism employs a disk 50, which is secured to the overhung end of a vertically mounted shaft 51, which shaft is mounted to turn in an arm, as 11, of the main frame. The disk 50 is provided with 55 a groove, as 52, which extends about its peripherally. This groove is shown as being made slightly eccentric to the outer periphery of the dog and to its axis. This gives it a sufficient depth that, at one point, it may be

60 provided with a holding slot, as 53, into which the wire may be inserted and bent upwardly. When this is done it will hold the wire sufficiently well that, by turning the disk 50, the wire may be drawn quite tightly.

65 The disk is separated from other parts so as

to permit free passage of the wire across its face.

The turning of the disk is done through a lever, as 6, which is mounted upon the shaft 51 and which is provided with any 70 kind of a suitable ratchet or dog device, so that continuous turning of the shaft may be obtained through an oscillating movement of the lever. A holding dog, as 60, engaging with a ratchet wheel 61, serves to hold the 75 shaft against backward movement.

Alongside of each of the wire holding bars 2 and 20, is placed a cutter bar. These two cutter bars are shown in Figures 4 and 5, each of these being mounted for reciprocating movement in guides carried by the frame. Each of these also acts to cut its respective wire by an upward movement. One of these acts to cut off the surplus portion of the one end of the wire and the other to 85 cut off the surplus portion of the other end of the wire. In consequence of this, these cutters will vary a little in their shape.

The cutter 7 shown in Figure 4, this being the cutter which is at the left hand side in 90 Figures 1 and 2, is designed for cutting the surplus portion of that end of the wire which is held by the dog 4. As this end lies inside of or behind the other end, this cutter is designed for cutting that wire which lies 95 next to it, as is clearly shown in Figure 4. The other cutter, 70, has its cutting edge 71 located farther out, or in position to cut the outside end of the wire, as is clearly shown in Figure 5. It is also provided with a 100 notch, as 72, located between the cutting surface and the body of the cutter, into which the innermost of the two wires may pass when the cutter is raised.

Each of these cutters is provided with a 105 downwardly facing surface 73 toward the upper end thereof, which is adapted to be engaged by a toe 81, carried by a yoke 8, which yoke is pivoted at 80. This yoke extends across the face of the machine a sufficient distance so that it may operate both of the cutters at once. It is provided with two such toes, as 81, one engaging with the cutter 7 and the other with the cutter 70, so that both are operated simultaneously. The 110 yoke 8 is also provided with an operating lever 82.

Each of the cutters, 7 and 70, co-operates with its respective wire-holding bar 20 and 2, to cut the wire. These holding bars 20 120 and 2 form the other half of the cutting mechanism. The wires are thus cut very close up to the twist and there can be no material length of wire projecting to engage with other goods or to in any way do harm. 125

The cutter 7 which is at the left hand side of the machine, as shown in Figures 1 and 2, is provided with a lug or projection 74, which is so placed with relation to a notch 44 formed in the adjacent edge of the wire 130

holding dog 4, that when the cutter is raised it will act as a cam to force the holding dog outward and thus release the end 14 of the wire held thereby, so that when this is cut

5 the remnant will be freed.

In connection with the dog 4 I have shown a lever 9 which is pivoted at 90 upon the frame and is provided with a tooth 91, adapted to engage with a recess 45 formed 10 in the face of the dog 4, when said dog is thrown outward. It thus holds the dog 4 in position for free insertion of the wire end. This locking lever holds the dog only lightly, so that a slight pressure will release the 15 same and throw it down into engagement with the end of the wire, when the same has been inserted.

The operation of my device is believed to be evident. In commencing the operation, 20 the operating lever 33 is thrown backward into horizontal position. In this position the slot 30 of the twister wheel will face outwardly and register with the slots both in the frame and in the wire holding bars 2 and 25 20. The end 14 of the wire is then placed under the holding dog 4 and the wire passed into the slots in the device, about the box and back and then again in the same slots. The wire is then placed into the peripheral 30 groove in the disk 50 and then brought upward into the holding notch 53. This tightening disk 50 is then turned until the wire has been drawn taut. The next step is swinging the operating lever 33 forward.

35 The mechanism herein shown is so proportioned that one swing of the lever, which is through 180°, will give the twister wheel three complete turns. The number of turns is, however, immaterial, except that it should 40 be enough to furnish a good twist and make a knot which will securely hold. As a matter of fact, the movement of the lever should be slightly more than enough to give the three full turns, the surplus being just 45 enough so that the natural backward turn of the twister, due to the resiliency of the wire, will leave the twister wheel in position so that its wire receiving slot registers with the slots in the other parts of the mechanism. After the twist has been made the 50 lever 82 is drawn forward which pulls up

the cutters 7 and 70, and cuts off the surplus wire. The wire is then slipped out of the tool, or rather, the tool is forced backward away from the knot.

55

What I claim as my invention is:

1. In a wire tying tool, means for twisting together two parallel wires, and cutters movable from below to cut the surplus wire ends at each end of the twist.

60

2. In a wire tying tool, means for twisting together two parallel wires, wire cutters each having a member mounted for vertical movement, one at each end of the twist, said movable members each having an arm extending under the wires and having an upwardly facing cutting edge positioned to engage only one of the wires.

65

3. A wire tying tool as in claim 1, having a cutter at each end of the twist cutting by 70 an upward movement, and a pivoted cutter-operating lever having a yoke end adapted to engage both of said cutters to operate them.

75

4. In a wire tying tool of the class described, means for twisting together parallel wire ends, and eccentrically pivoted wire holding dog for one end of the wire, a cutter between said dog and the twister, and means for releasing said dog by the cutter during 80 the cutting movement.

80

5. In a wire tying tool of the class described, means for twisting together the parallel wire ends, a clutch dog for holding one end of the wire, a wire cutter adapted to 85 cut the wire between said dog and the twister, said dog and cutter having cam surfaces engaging to automatically release the dog by the cutting movement of the cutter.

85

6. In a wire tying tool of the class described, means for twisting together the parallel wire ends, an eccentrically pivoted wire holding dog, a cutter between said dog and the twister adapted to cut the wire held by 90 said dog, said cutter and dog having parts 95 engaging during the cutting movement of the cutter to move the dog into release position.

90

Signed at Seattle, King County, Washington, this 15th day of January, 1920.

GEORGE WOOD.
